JAMES PATERSON, OF ELIZABETH, NEW JERSEY, ASSIGNOR TO THOMAS POTTER, SON & CO., OF PHILADELPHIA, PENNSYLVANIA.

Design No. 4,415, dated October 11, 1870.

DESIGN FOR AN OIL-CLOTH PATTERN.

The Schedule referred to in these Letters Patent and making part of the same.

I, JAMES PATERSON, of Elizabeth, county of Union, State of New Jersey, have invented or produced a Design for an Oil-Cloth Pattern, of which the following is a specification.

The figure in the accompanying drawing illustrates my design for an oil-cloth pattern, which consists of a series of bordered stripes, A, arranged at right angles to similar stripes, B, one series of stripes passing under and over the other, as clearly represented in the drawing.

The borders may be ornamented between the lines, as shown at x, or otherwise, and the oblong spaces y between the stripes may be varied like marble, or otherwise ornamented.

Irrespective of the colors employed and of the minor ornamentation,

I claim—

An oil-cloth pattern, consisting of a series of bordered stripes, arranged in respect to each other, as set forth.

In testimony whereof I have signed my name to this specification in the presence of two subscribing witnesses.

JAS. PATERSON.
